CLAIM

The ornamental design for a tissue anchor delivery tool, as shown and described.

DESCRIPTION

FIG. 1 is an isometric view of a tissue anchor delivery tool. FIG. 2 is a front side view of the design for the tissue anchor delivery tool.

FIG. 3 is a back side view of the design for the tissue anchor delivery tool.

FIG. 4 is a top side view of the design for the tissue anchor delivery tool.

FIG. 5 is a bottom side view of the design for the tissue anchor delivery tool.

FIG. 6 is a right side view of the design for the tissue anchor delivery tool; and,

FIG. 7 is a left side view of the design for the tissue anchor delivery tool.

The portions of the article shown in broken lines form no part of the claimed design.
